UNITED STATES PATENT OFFICE.

WALTER BALL, OF HUBBARD, OHIO.

AUTOMATIC AIR RELEASE.

1,414,249.

Specification of Letters Patent. Patented Apr. 25, 1922.

Application filed March 5, 1921. Serial No. 449,857.

To all whom it may concern:

Be it known that I, WALTER BALL, a citizen of the United States, residing at Hubbard, in the county of Trumbull and State of Ohio, have invented certain new and useful Improvements in Automatic Air Releases, of which the following is a specification, reference being had therein to the accompanying drawing.

10 The present invention relates generally to air compressors, and aims to provide a novel and useful device for releasing the air from within the opposite ends of the air compressor cylinder during the starting 15 of the compressor, whereby to facilitate starting.

Difficulty has been experienced in the starting of air compressors by electric motors which are used for driving them, such 20 as air compressors used in garages for supplying compressed air for inflating pneumatic tires, owing to the fact that when the electric motor is started, the resistance of the air within the compressor will create 25 considerable strain on the belt connecting the motor and compressor, and such belt will frequently slip in starting, so as to burn by the friction, or to break. Also, the strain imposed on the motor is apt to injure 30 same by the excessive load of electrical current, causing the motor to burn out. Such objectionable conditions are remedied by the present device, which is operable to release the air from the compressor during the 35 starting of the motor, whereby the compressor will offer little or no resistance during the starting thereof by the motor, until the motor and compressor pick up their speed, at which time the air released is rendered 40 inoperative.

Another object of the invention is the provision of such a device operated automatically with the motor, when same is started, whereby to release the air from the 45 compressor until the motor has assumed running conditions.

A still further object is the provision of such a device comprising a novel and improved construction and assemblage of 50 parts, providing for practical and efficient operation, as well as a simple and inexpensive appliance.

With the foregoing and other objects in view, which will be apparent as the description proceeds, the invention resides in the construction and arrangement of parts hereinafter described and claimed, it being un-

derstood that changes can be made within the scope of what is claimed, without departing from the spirit of the invention. 60

The invention is illustrated in the accompanying drawings, wherein—

Figure 1 is a plan view of the device as applied to the air compressor, portions being shown in section. 65

Fig. 2 is a side elevation of the device.

Fig. 3 is an enlarged cross section on the line 3—3 of Fig. 2.

Fig. 4 is an enlarged end view of the solenoid. 70

Fig. 5 is a diagrammatical view of the air compressor apparatus with the device installed.

Fig. 6 is a detail diagrammatical view showing the motor circuits in running position of the motor control. 75

The air compressor apparatus is composed, as usual, of the air compressor cylinder 10 in which the piston 11 operates, and the piston rod 12 is connected by a pitman 13 with a crank shaft 14 on which a pulley wheel 15 is secured. An endless belt 16 passes around the pulley wheel 15 and a pulley wheel 17 of the electric motor 18 which drives the air compressor. The motor 18, as shown, is of two phase type and has the two circuits 19, which are controlled by a motor control or starter including the resistance 20 adapted to be disposed in said circuits when starting the motor, as seen in Fig. 5, and which resistance is cut out of said circuits when the starter assumes running position, as seen in Fig. 6. Such resistance thus protects the motor, during starting, until the motor and compressor have picked up their speed. 90

Even though an automatic starter is used for starting the motor, still, the air compressor will offer considerable resistance against the starting movement of the armature of the motor, which strain is imposed on the belt 16 and the strain and resistance is injurious to the belt as well as the motor, and not infrequently causes the belt to burn or break, with attendant annoyance 100 and expense.

In carrying out the invention, an air release device is used with the air compressor, and includes a valve comprising a block or casing 21 having a longitudinal bore 22 extending therethrough in which a valve member or plunger 23 is slidable longitudinally. The block 21 has the pairs of ports 24 and 25 in the opposite sides thereof, and the valve 110

member 23 has annular channels 26 to move into registration with the ports 24 and 25 simultaneously, as seen in Fig. 1. The ports 24 open into the atmosphere, while the ports 5 25 are in communication with the opposite ends of the chamber of the cylinder 10. Thus, a piece 27 is secured to that side of the block 21 which has the ports 25 by means of screws 28, or the like, and said plate has 10 openings 29 registering with the ports 25 and into which the adjacent ends of a pair of pipes 30 are secured in communication with the ports 25, while the opposite ends of said pipes are engaged through the wall 15 of the cylinder 10 in communication with the interior of said cylinder. Thus, when the valve member 23 is slid to open position, as seen in Fig. 1, with the channels 26 registering with the ports 24 and 25, the ends of the 20 air compressor cylinder 10 are opened to the atmosphere by way of the pipes 30, ports 25, channels 26 and ports 24, which will permit the air to escape when the piston 11 is reciprocated. However, when the valve member 25 18 is slid to remove the channels 23 from the ports 24, this will close such air escape outlets.

The plate 27 and block 21 have a lubricant duct 31 extending to the bore 22 between the 30 ports 25, for injecting lubricant to lubricate the surfaces between the block 21 and valve member 23.

Automatic means is provided for operating the air releasing valve whereby to open 35 such valve when the motor 18 is started, and to then close the valve when running conditions are obtained. Such means includes a solenoid 32 disposed in alinement with the valve, and having the end plates 33. These 40 plates 33 have supporting portions 34 extending laterally from the solenoid (downwardly as shown) to seat on or bear against a longitudinal supporting bar, 36, and said portions 24 have lugs 35 to overlap the opposite edges of the bar 36, to guide the solenoid 45 for sliding adjustment along the bar 36. Clamping rods 37 are bent to embrace the solenoid and their terminals project from the solenoid across the opposite edges of the 50 bar 36 and pass through transverse clamping strips 39 extending across the bar 36 opposite to the solenoid, and nuts 38 are threaded on the terminals of the rods 37, whereby to clamp the strips 39 and end plates 33 against the bar 36. By loosening the nuts 38, the 55 solenoid is released, so that it can be slid or adjusted longitudinally along the bar 36, when it is desired to regulate the pull exerted on the core or plunger 40 of the solenoid 60 which projects from that end thereof adjacent to the valve. The solenoid has a central tube 44 in which the core 40 is slideable and around which the coil is wound.

The operative connection between the 65 valve and solenoid includes a longitudinal

rod 41 extending through central bores with which the valve member 23 and core or plunger 40 are provided, and said plunger and valve member are secured in position on said rod by means of the respective nuts 42 and 70 43 threaded on said rod, the rod being threaded from end to end.

The bar 39 is supported from the valve block 21, which is in turn supported by the pipes 30 from the air compressor, thus providing a simple and convenient means for the support and positioning of the air release. Thus, a Z-bracket 45 has one flange secured to the bottom of the block 21, by 75 screws 46, or the like, and the other flange is 80 clamped on the bar 36 by means of bolts 47, or the like. The bar 36 is thus supported from the block 21, and in turn supports the solenoid.

The rod 41 is spring-pressed to control its 85 movement and return the valve to closed position, when the solenoid is deenergized. To this end, a pair of longitudinally spaced posts 48 and 49 are secured on the bar 36 beyond that end of the valve opposite to the 90 solenoid, and the rod 41 extends slidably through said posts. Pairs of nuts 50 and 51 are threaded on the rod 41 between the posts 48 and 49, and coiled limiting and cushion or buffer springs 52 and 53 are disposed on 95 said rod between the posts 48 and 49 and the nuts 50 and 51, respectively. The springs 52 and 53 will be compressed by the opening and closing movement of the valve, to limit such movements of the valve, and to also cushion the valve in opening and closing. A returning spring 54, which is a coiled expansion spring, is disposed on the rod 41 and is confined between the post 48 and nuts 55 threaded on that terminal of the rod opposite to the solenoid. The nuts 50, 51 and 55 can be adjusted to regulate the tension of the springs, and the tension of the spring 54 will serve to return the valve to closed position.

In order to energize the solenoid 32 during the starting of the motor 18, such solenoid is disposed in one of motor circuits, during starting. Thus, as shown in Fig. 5, the leads 56 of the solenoid are connected to one 115 circuit 19 to interpose the solenoid 32 in the circuit in series, although other connections of the solenoid with the motor circuits or starter can be used according to the conditions. In some cases, the solenoid can remain in the motor circuit, whereby the electrical current during the starting of the motor is sufficient so that the energization of the solenoid is sufficient to pull the plunger 40 and rod 41 against the tension of the 120 spring 54, whereas when the motor has assumed running condition, the tension of the spring 54 is sufficient to return the valve and solenoid plunger even though the solenoid 125 many remain energized. Such energization 130

of the solenoid during running conditions, however, is decreased from starting conditions, owing to the abnormal current strength during starting.

5. In operation, when the motor 18 is started, the solenoid 32 is energized whereby to pull its plunger or core 40 into the solenoid (to the right as seen in Figs. 1 and 2) thereby pulling the rod 41, and sliding the valve member 23 to opened position, as seen in said figures. The release valve is thus opened the moment the electrical current is supplied to the motor, whereby the air can escape from the air compressor, providing for the easy and rapid starting of the compressor. When the speed of the motor and compressor have reached running conditions, then the solenoid 32 is deenergized, such as cutting it out of the circuit, as seen 20 in Fig. 6, whereby the spring 54 will return the valve member 23 to closed position, thereby preventing the further escape of air. The spring 53 being compressed by the nuts 51 during the opening movement of 25 the valve member 23, will limit and cushion such movement, while the spring 52 will similarly limit and cushion the return or closing movement of the valve member under the influence of the spring 54. In 30 practice, it has been found that by so releasing the air, the motor and compressor will start quickly, and there will only be a few "hisses" of the escaping air, before running conditions are obtained, whereas 35 without the release of the air it requires considerable effort on the part of the motor to get the compressor into full operation. The device will relieve the belt 16 and motor 18 of the burden of strain during the starting 40 of the motor, until the speed is picked up, when the release valve closes.

Having thus described the invention, what is claimed as new is:—

1. The combination of an air compressor, 45 means for driving said compressor, air escape means for said compressor, and automatic means operable with the starting of said driving means for permitting the escape of air from said compressor.

50 2. The combination of an air compressor, an electric motor connected thereto for driving it, air release means for said compressor, and electrically-energized means operable, when the motor is started, for controlling 55 said means to permit the air to escape from said compressor.

3. The combination of an air compressor, driving means for said compressor, air release means for said compressor including 60 a valve, and automatic means operable when said driving means is started for opening said valve.

4. The combination of an air compressor, 65 an electric motor for driving said compressor, air release means for said com-

pressor including a normally-closed valve, and electrically-energized means operable simultaneously with the starting of said motor for opening said valve.

5. The combination with an air compressor, of a valve block having ports, means establishing communication between said ports and air compressor, a valve member 70 slideable in said block and having channels to register with said ports for the escape of air, and a solenoid in alinement with said valve member and having its plunger connected thereto.

6. The combination with an air compressor, of a valve block having ports, means 80 connecting said block and compressor for establishing communication between said compressor and ports and supporting said block, a valve member slideable in said block and having channels to register said ports 85 for the escape of air, a bar secured to and supported from said block, and a solenoid mounted on said bar and having its plunger connected to the valve member.

7. An air release comprising a valve block, 90 a valve member slideable in said block, a solenoid having a plunger connected to the valve member for moving the valve member in one direction for bringing the valve member to open position, means for moving the 95 valve member in the opposite direction to closed position, and spring means for limiting and cushioning the movement of the valve member in opposite directions.

8. An air release comprising a valve block 100 having ports, a valve member slideable in said block and having channels to register with said ports, a solenoid in alinement with said valve member having a plunger, to move the valve in one direction when the 105 solenoid is energized, means for moving the valve member in the opposite direction when the solenoid is deenergized, and spring means for limiting and cushioning the movements of said valve member in opposite directions. 110

9. An air release device comprising a bar, 115 a valve block secured to said bar and having ports, a valve member slideable in said block and having channels to register with said ports, a solenoid secured on said bar having a plunger in alinement with said valve member, posts carried by said block, a rod secured within said valve member and plunger and slideable through said posts, limiting and cushioning springs on said rod bearing against said posts, members carried by the rod to contact with said springs when the valve is opened and closed, and a returning spring on the rod bearing against one post for moving the valve to return same and said plunger when the solenoid is deenergized. 120

In testimony whereof I hereunto affix my signature.

WALTER BALL.
